UNITED STATES PATENT OFFICE

ATTILIO HENRY GIUSTI, OF PHILADELPHIA, PENNSYLVANIA

IGNITION INDICATOR

Application filed November 18, 1929, Serial No. 408,117. Renewed February 7, 1931.

The invention aims to provide an exceptionally simple and inexpensive, yet a highly efficient and desirable indicator for determining whether the ignition system of a motor is operating properly or improperly.

The invention is intended primarily for use with machines having twin ignition systems, in which one set of spark plugs is fed from one coil by means of a breaker and distributor, while the other set of plugs is similarly fed by means of a second coil and a second distributor and breaker, the two distributors and breakers being commonly embodied in one unitary construction. When used in connection with such a system, it may be determined at any time whether the primary circuit for either set of plugs is functioning properly or improperly, and the invention is of particular advantage in locating breaker-point trouble.

With the foregoing in view, the invention resides in the novel subject matter herein-after described and claimed, description being accomplished by reference to the accompanying drawings.

Fig. 1 is an elevation of an ignition indicator constructed in accordance with my invention, for use upon a twin ignition system.

Fig. 2 is a vertical sectional view on line 2—2 of Fig. 1.

Fig. 3 is a diagram showing the manner in which the indicator is connected with a twin ignition system.

The drawings above briefly described illustrate the preferred form of construction and while such construction will be herein specifically explained, it is to be understood that within the scope of the invention as claimed, variations may be made.

The numeral 5 denotes an insulating panel which may be secured to an instrument board B in any desired way, so as to extend across an opening O in said board. Mounted upon the panel 5, are two ignition indicating units U, but as the constructions of both are identical, only one will be described.

The unit U embodies two L-shaped members 6, each having an elongated threaded shank 7 and a lateral head 8. The two shanks 7 pass through openings 9 in the panel 5 and

are provided with shoulders 10 which abut the front side of said panel, said shoulders being preferably in the form of nuts threaded upon the shanks. Clamping nuts 11 also threaded upon these shanks, abut the rear side of the panel 5 and thus secure the two members 6 rigidly to said panel.

Threaded into the heads 8 and projecting beyond the outer ends of these heads, are two electrodes 12 which are spaced apart to provide a spark gap 13. A transparent tube 14 surrounds the projecting portions of the electrodes 12 and is held in place by recesses 15 formed in the outer ends of the heads 8, said recesses snugly receiving the ends of said tube.

Binding posts 16 are threaded into the shanks 7 and have their inner ends in contact with the electrodes 12, while their outer ends project beyond said shanks and are provided with wire clamping nuts 17.

In connecting the indicator with a twin ignition system, the usual high tension leads L from the coils C to the distributor and breaker unit D, are connected with the binding posts 16 as diagrammatically illustrated in Fig. 3. The portions of the leads connected with the coils C, are connected for instance with the lowermost of the four binding posts 16, and the portions of the leads passing on to the distributor and breaker unit D, are connected with the other two of said binding posts. Thus, each time high tension current flows through the ignition system, a flash or spark is created at the spark gaps 13. Hence, at a glance, the driver of the vehicle may determine whether the current feeding means for one set of plugs or the other, or both, are operating properly or improperly. The invention is of particular advantage in locating breaker-point trouble, although by failure to show a flash or spark at the gap 13, will also indicate any other ignition trouble which may be causing the plugs to miss.

I claim:

1. In an ignition indicator, a support having two spaced openings, two L-shaped members each having a threaded shank and a lateral head, said shanks passing through said

- openings and having shoulders abutting one side of said support, nuts threaded on said shanks and abutting the other sides of said support, electrodes projecting from the outer 5 ends of said lateral heads and spaced apart to provide a spark gap, and binding posts in conducting relation with said electrodes and projecting beyond the free ends of said shanks.
- 10 2. A structure as specified in claim 1; together with a transparent tube surrounding said electrodes, said outer ends of said heads having recesses snugly receiving the ends of said tube.
- 15 In testimony whereof I have hereunto affixed my signature.

ATTILIO HENRY GIUSTI.
